UNITED STATES PATENT OFFICE.

ERNEST E. CLAYS, OF SALT LAKE CITY, UTAH.

BALL-COUPON DISTRIBUTOR.

Application filed April 6, 1925. Serial No. 21,155.

To all whom it may concern:

Be it known that I, ERNEST E. CLAYS, citizen of the United States, residing at Salt Lake City, in the county of Salt Lake and State of Utah, have invented certain new and useful Improvements in Ball-Coupon Distributors, of which the following is a specification.

My invention relates to coupons distributors, and has for its object to provide a ball coupon distributor by which any number of balls or spheres may be mixed within a closed container, and allowed to fall by gravity into a contracted neck portion of said container and from which they are individually distributed at its lower end by a manually operated release plunger, and exposed to sight.

These objects I accomplish with the device illustrated in the accompanying drawings in which similar letters and numerals of reference indicate like parts throughout the several views, described in the specification forming a part of this application and pointed out in the appended claims.

In the drawings in which I have shown the best and most substantial embodiment of my invention, Figure 1 is a side elevation of the device. Figure 2 is a vertical transverse section on line 2—2 of Figure 4. Figure 3 is an end elevation of the device, and Figure 4 is a plan view of the device.

The device consists of a rectangular box A having a glazed detachable cover B. A supporting standard C is secured on each end of said box, and each of said standards consists of a vertical member 1 with brace members 2. A horizontal shaft 3 connects the upper ends of said standards C, and on which shaft is carried the ball container D. The ball container D is a cylindrical member having diametrically disposed trunnion sleeves 4, secured thereto, and which sleeves are journaled on said shaft 3. A closure plate 6 is fastened in the upper end of said container D by the detachable lock bar 7, which may have a small padlock attached thereto to lock said cover in place. A lock rod 8 is placed through said container D and with its ends engaged with the vertical standard members 1 to retain the said container D in a vertical position, except when it is desired to mix the balls carried in said

container. The lower end of said container D is given a tapered form to provide a discharge or contracted neck portion 10 having a central bore of the size to allow the ball coupons to fall loosely to the discharge or lower end of said neck 10. To prevent any stoppage of the balls as they enter said neck portion 10, I provide a sleeve 11 which is loosely carried on the said neck 10, with upwardly extended plunger bars 12 integral with said sleeve, and with the upper end portion of said bars 12 passed through ports 13 in the wall of the taper portion of said container D. On the lower end of said neck 10, I attach a guide member 14, within which is manually operated a U-shaped gate member E. A circular opening 15 is provided in the lower leg 16 of said gate member E to allow the ball coupons to pass through, when the said gate is operated and to normally hold the balls within the said neck and with the lower one resting on the said lower leg 16. A horizontal slot 20 is cut into the side of said neck 10 to receive the end portion of the leg 17 of said gate member E when the gate member is operated, and to hold all of said balls within said neck above said leg 17 when the one ball is held by the lower leg 16. A stem 18 is attached to the medial portion of said gate member E, and a spiral spring 19 carried thereon returns said gate member E to its normal position, shown in Figures 1 and 2. A sight opening 21 is cut in the side wall of said neck 10, which opening is smaller than the balls to be used in order that the ball supported by the lower leg 16 may be seen but will not pass out through said opening 21. A hole 22 is provided in the glass portion of the cover B, which hole is in alignment with the discharge end of said neck 10. A trough 23 is secured within said box A with one end thereof positioned below the said hole 22, and with the bottom of said trough inclined downwardly to support a number of balls released from the neck 10 of the container. A spring strip 24 is normally held against the lower end of said trough and a detachable end therefor, and a spring plunger rod 25 is supported within said box A with one end protruding from said box and its other end bearing against said strip 24, whereby the said strip

may be pushed away from the end of the trough to allow the balls 27 to fall from the trough to the interior of said box.

Having thus described my invention I desire to secure by Letters Patent and claim:

- 5 1. In a device of the class described the combination of ball coupons differently colored to represent value; a container within which said balls are mixed; a shaft on which
- 10 said container is rotatable for mixing said balls; means of locking said container in a vertical position; a contracted depending neck portion having a sight opening near its lower end, and a horizontal slot trans-
- 15 verse to and above said sight opening; a guide secured to the free end of said neck portion; a U-shaped gate member operable in said guide member and having a hole in the lower leg of said gate member; a stem
- 20 secured to said gate member, carrying a spiral spring thereon; a box carrying standards to which said shaft is secured; a glazed cover for said box; and opening in the glass

of said cover in alinement with the discharge of said neck portion; a trough secured at an 25 incline within said box with one end thereof under the hole in said glazed cover and a spring strip adapted to form the other end of said trough; and means to move said strip away from said trough to allow the 30 balls in said trough to fall into said box.

2. In a device of the class described the combination of ball coupons marked to indicate the different values; a container adapted for lateral rotation to mix said 35 coupons; a normally depending neck portion having a sight opening means to open and close the said neck whereby a single coupon will fall from the said neck, a box beneath said neck having a glazed cover, with a hole 40 in the said cover in alinement with the bore of said neck.

In testimony whereof I have affixed my signature.

ERNEST E. CLAYS.
